By Wilkinson & Hulley
J. H. Hulley

UNITED STATES PATENT OFFICE.

VICTOR L. CUNNYNGHAM, OF CHICAGO, ILLINOIS.

ADVERTISING-RECORD CHART.

1,348,349.

Specification of Letters Patent.

Patented Aug. 3, 1920.

Application filed November 10, 1919. Serial No. 337,099.

To all whom it may concern:

Be it known that I, VICTOR L. CUNNYNGHAM, a citizen of the United States, residing at Chicago, in the county of Cook and State 5 of Illinois, have invented certain new and useful Improvements in Advertising-Record Charts, of which the following is a specification.

The primary object of this invention is to 10 provide a system whereby advertising data ordinarily recorded through means of words and figures, and therefore requiring mental calculation or imagination in appreciating the sum of its effect, may be so recorded by 15 the graphics of a code of colored or shaded geometrical indicia that while leaving individual entries separately intelligible as to the items they represent, the arrangement of the indicia in inter-related groups, for 20 example, columns and lines standing, respectively, for factors in the record to be produced, for example, subdivisions of the calendar year and different mediums of publicity, will develop a composite picture that 25 will graphically express an aggregate effect of the whole or any section of the advertising, and communicate such effect by mental impression allied to that aimed to be produced by the advertising itself. Associated 30 with the graphics may be any desired words expressing any information in addition to that imparted by the picture, or figures indicating circulation, cost of space, etc., in the particular medium. The color scheme 35 and space, however, will both be indicated by the geometry of the indicia; the color information involving coloring or shading of the indicia as well as the geometry thereof.

As a result of this system, in a consultation 40 between an advertising agent and, for example, the publicity official of a business house, the former is enabled to impart to the latter, instanter, the information concerning an advertising campaign proposed, in 45 course of execution, or completed, and the latter acquires at a glance and without calculation a mental picture of the whole campaign, the degree of aggressiveness characterizing the same at different subdivisions 50 of the calendar year or through different available channels, as well as the distribution through all of such channels, the color schemes entering into the advertisements or 55 which characterize the advertisements by seasons and by circulating mediums, and, in short, a comprehensive appreciation of the

entire situation; and he acquires it through a mental impression, in kind, like that which the advertisements themselves impart; in other words, the record becomes a matter of 60 psychology just as the advertisement is intended to be.

In order that the invention may be fully understood, two charts, reproduced from actual records developed according to the 65 present invention, are shown in the accompanying drawings by way of illustration, in which—

Figure 1 is a chart in which multi-colored 70 indicia are used and referred to as chart B; and

Fig. 2 is a chart in which single color indicia are used and referred to as chart A.

A chart is subdivided into a vertical column space 1 for the names of publications or circulating mediums; column spaces 2 for months or other subdivisions of the calendar year or other time periods; column spaces 3 preferably for figure totals; and line spaces 4 intersecting the column spaces 5 for the purpose of locating in the several column spaces indicia and other data to be associated with the name of the publication occupying that portion of the line space which is in the publication column 1. Associated 80 with the name of each publication in the publication column are preferably figures 6 indicating the circulation of the publication, while at the intersections of the line space of the particular publication with 90 those particular columns corresponding with the time subdivision or publication issue for which an advertisement had been purchased, is preferably expressed as at 7 the cost of the insertion, and the total cost of the insertions 95 for the year or other period of time is carried out in the line space 8, while the circulation multiplied by the number of insertions is shown in the total circulation line space 9, and these two aggregates stand side by side 100 in order that the ratio of cost to circulation can be determined.

Within the frames developed by the intersection of columns with line spaces are located the indicia which characterize the 105 present invention. These are in the form of geometrical figures 5. These indicia are preferably in the form of circles, although they might be square or polygonal, and they have their surfaces subdivided into sectors 110 5^a, 5^b, 5^c, and 5^d which qualify their significance. For instance, if a circle is subdivi-

vided into four sectors, some of which may comprise shaded or colored sectors 5^a—5^d, it means a four-color advertisement; if divided into three sectors, 5^a, 5^c, 5^d, it indicates 5 a three-color advertisement; and if it contains but a single shading or color 5^x it means a single color advertisement. The single color circles are varied to indicate proportions of a page covered by the advertisement; thus a single color circle may have proportions of its surface colored and the remainder left uncolored, as, for instance, the shaded segment 5^{x'} associated with the unshaded three-quarters 5^{x2} to indicate a quarter page. By "shading" and "coloring" as herein used, I intend to convey the idea of rendering the surface of the geometrical figure or subdivision thereof different in appearance from the surface of the surrounding field.

Associated with the chart is a key 10 showing typical indicia, together with explanation of their meaning. While geometrical subdivisions of the circle, as well 25 as the coloring thereof are more or less arbitrarily selected in establishing the code, they nevertheless contribute to a graphical representation of the conditions to be expressed, and thus serve the purpose herein-before recited.

As shown in the drawings, A and B are two charts showing a pictorial representation of an advertising campaign for two products of one concern, or two lines for 35 which advertising is contemplated and which are represented graphically, and also summarized as shown at the bottom of chart B to enable the purchaser of the advertising matter to ascertain quickly the scope of the campaign planned. It will be noted from 40 reference to the drawings that chart A is arranged to represent advertising in four groups of publications. The chart indicates the kind of advertising contemplated for 45 every month in every one of the various publications. It includes also data indicating the cost per insertion and data showing the circulation of the various publications, the same being utilized for every one of the 50 four classes and all being carried to grand totals at the bottom of the chart.

The chart B represents advertising planned in four classes of magazines, the scheme being the same as that shown by 55 chart A. However, chart B, as shown in the drawings, includes the totals for the arrangement of the classes of publications shown thereon and also a summary of the totals of charts A and B. In the summary 60 the line space 11 includes the figures shown in the line space 12 of chart B. The figures in line space 13 include the totals in line space 14 of chart A, and line space 14 on chart B is the sum of the figures in line 65 spaces 11 and 13 thereon. The line space

15 of the summary shows the total circulation per month set forth in line space 16 of chart B. In like manner line space 17 includes the totals shown in line space 18 of chart A, and line space 19 shows the sums 70 of the figures in line spaces 15 and 17.

These charts have been employed to show to a purchaser, contemplating an advertising campaign, what his expenses every month would be, in what magazines his advertisements are appearing, and also the nature of the advertisements, the latter being indicated by the particular arrangement of the geometrical figures 5. Shown also in the charts at 6 are the circulation of the various magazines so that the purchaser may calculate at any time his cost per publication, pro rata the same with the circulation, or determine any other figure which may be desirable to know. As submitted to 80 the prospective purchaser the geometrical figures on the charts would preferably be indicated in colors, and which colors would be fully explained in the key 10.

The charts as above stated have been prepared to show a specific advertising campaign, contemplated or ordered, the kinds of advertisements and amount of space to be utilized being graphically represented, the names and circulations of the various 90 publications and the cost per advertisement being also shown on the charts in association with the graphic data, and the whole being arranged so that the figures of the line spaces and columns will represent totals 95 which it is desirable to know not only in planning the advertising campaign but as the same is progressing. With charts such as those shown in the drawings, an advertisement purchaser would have before him 100 data whereby at a glance he might ascertain what is being done in any particular month or other period of time as such information is found necessary.

I claim:

1. An advertising graphic record chart comprising geometrical indicia for the individual entries to be recorded, sub-divided into distinguishable areas, and with their different subdivisions differentiated geometrically; said indicia being arranged in inter-related groups comprising columns and lines corresponding to factors in the record to be produced, and being adapted by their collocation to develop a composite 115 picture graphically expressing the aggregate effect of the items which they severally represent.

2. An advertising record chart comprising column spaces and line spaces intersecting to develop frames for locating items of the record, the column spaces corresponding to subdivisions of a calendar year, and the line spaces corresponding to advertising 125 mediums; geometrical indicia located in 130

said frames individually expressive of color schemes and advertising insertions which they severally represent; the indicia having their surfaces subdivided geometrically and 5 their geometrical subdivisions differently colored; and the grouping of the indicia developing a composite picture graphically

expressing the aggregate effect of the advertising items which the indicia individually represent.

10

Signed at Chicago, Illinois, this 10th day of October, 1919.

VICTOR L. CUNNYNGHAM.
